UNITED STATES PATENT OFFICE.

CHARLES N. SOWDEN, OF TORONTO, ONTARIO, CANADA.

SLICING MACHINE.

Application filed March 8, 1923, Serial No. 623,675. Renewed September 24, 1925.

To all whom it may concern:

Be it known that I, CHARLES N. SOWDEN, a subject of the King of Great Britain, and resident of the city of Toronto, county of York, Province of Ontario, in the Dominion of Canada, have invented certain new and useful Improvements in a Slicing Machine, described in the following specification and illustrated in the accompanying drawings, that form part of the same.

The principal objects of the invention are to greatly simplify the construction of this type of machine and to devise a very efficient machine which may be sold at a price which will enable its use by small dealers.

Further objects are to devise a neat and very compact machine which will be very positive in its operation.

The principal feature of the invention consists in the novel construction and arrangement of parts, whereby the revolving knife is operated with an oscillating movement having a return action more rapid than the feed, and whereby the material to be cut is securely clamped with a balanced arrangement of levers, enabling rapid adjustment and further, in the novel arrangement and construction of the feed mechanism for the holding table.

In the drawings, Figure 1 is a perspective view of the machine partly in section.

Figure 2 is a side elevational view showing the main frame in longitudinal section.

Figure 3 is a vertical sectional view through the line 3—3 of Figure 2.

Figure 4 is a sectional view through the oscillating knife carrying arm and the supporting casing.

Figure 5 is a cross section through the line 5—5 of Figure 2.

Figure 6 is a sectional elevational view illustrating a modified construction of the table feed mechanism.

Figure 7 is an enlarged sectional perspective view of the table feed clutches.

Referring to the drawings, the base 1 is formed with an upright casing 2 at one end to the outer face of which is secured the cover 3 closing the circular opening 4. The cover 3 carries a suitable journal for the main drive shaft 5 to which is secured the fly wheel 6 provided with a handle 7 for operating same. On the inner end of the shaft 5 is secured a spur gear 8 which meshes

with a pinion 9 secured upon a shaft 10. The shaft 10 is supported in ball bearings 11 mounted in a sleeve 12 which is rotatable in a bearing 13 in the inner side of the upright casing 1.

To the inner end of the sleeve 12 is secured an arm 14 which extends upwardly within the casing 2 and is formed with a longitudinal groove 15 in its outer side. A roller pin 16 secured to the inner face of the spur gear 8 extends into the groove 15 and as the gear is rotated the roller pin moves back and forth in the grooved arm, swinging the arm with an oscillating motion. This motion will not be uniform because as the gear revolves anti-clockwise the roller pin moves outwardly in the grooved arm first imparting very little oscillating motion, then through the upper half of its orbit it swings the arm with a uniform movement forwardly and downwardly and it then begins to move inwardly in the groove so that the movement of the arm in its return to the upright position is swung very rapidly because the roller approaches very closely to the pivot point of the arm.

The outer end of the sleeve 12 is provided with an upwardly extending arm 17 in the form of a flat hollow casing and in this casing are mounted a pair of spur pinions 18 and 19, the lower pinion 18 meshing with a pinion 20 on the shaft 10.

The cover 21 of the arm 17 is formed with a bearing boss 22 at its upper end in which the spindle 23 is journalled. This spindle is provided with a pinion 24 at the inner end meshing with the pinion 19 and at the outer end it carries the circular knife 25. The knife is thus revolved through the train of gears described initially operated by the spur gear 8, and the arm 17, being rigidly connected with the inner arm 14, is oscillated by the operation of the spur gear through the roller pin 16.

A guard 26 is secured to the boss 22 surrounding the knife. This guard is preferably formed in two halves having hinged clamps 27 provided with thumb screws 28 so that the cover may be readily loosened and swung clear of the knife to allow of cleansing. Each of the cover sections is pivoted on the boss 22.

A bracket 29 is rigidly secured to the base 1 at the opposite end from the upright cas-

ing 2 and is provided with a pair of longitudinal parallel rods 30 upon which is slidably mounted the carriage 31.

A plate 32 preferably corrugated longitudinally rests upon the inward end 33 of the bracket and is rigidly supported at the outer end on the rod 30. A tray 34 formed of sheet metal preferably having a transversely corrugated surface 35 and an upturned serrated inner edge 36 is removably secured to the carriage. The meat or other material to be cut is adapted to be placed upon this tray.

The carriage is provided with a pair of arms 37 extending upwardly either side of the plate 32 and pivotally mounted in the upper ends of these arms above the plate are the bell crank arms 38, the inwardly extending members of which are provided with pivotally serrated gripper members 39.

The outer and upwardly extending members of the bell cranks are connected by a link 40 and a lever 41, the link being connected to the lever intermediate of its length. When the lever is thrown inwardly both of the bell crank members swing outwardly thus throwing the inner members carrying the grippers away from the table to allow the placing of the meat to be cut.

The bell crank members are provided with spiral springs 42 which tend to force the gripper members downwardly to hold the meat securely in place.

The carriage is provided with a downwardly extending arm 43 in which is pivotally supported an arm 44 carrying a pin 45 projecting downwardly to engage a spirally threaded shaft 46 extending longitudinally thereunder. The rotation of this shaft moves the carriage forward as the knife moves clear of the material to be cut. The shaft is operated by a pair of clutch members 47 and 48, the clutch 47 being shown in section in Figure 7.

The form of clutch shown is of the ball type, the spring held balls 49 engaging the cone 50 which is secured to the shaft. The clutch 47 is adapted to grip and hold the shaft from backward rotation, it being held in a stationary position by the rod 51 illustrated in Figure 3 or the rod 52 illustrated in Figure 6. This clutch member is provided with a pin 53 extending toward the member 48 and the member 48 is provided with a pin 54 adapted to engage the pin 53.

In the mechanism illustrated in Figure 3 the clutch 48 has connected to its outer side a bar 55 which extends upwardly and is pivotally connected to a bar 56 extending rearwardly and pivoted to the casing 2.

The arm 14 is provided with a pin 57 on its inward side which is adapted to engage the underside of the bar 56 to lift it following the backward swing of the knife arm and on being lifted the movement is trans-

mitted through the rod 55 to turn the clutch 48 to grip the shaft and turn it, thus through the worm and pin construction described, advancing the carriage.

The degree of advance is regulated by the rods 51 and 52 to bring the pin 53 on the clutch 47 into such a position as to engage the pin 54 to limit the return movement of the clutch 48. This adjustment can be regulated so that the feed shaft may be turned a very slight amount in order to produce a very thin slicing or may be turned to any degree to produce an extra heavy slice.

The adjustment of the rod 51 is effected through a thumb nut 58 but a more definite arrangement of graduation may be effected by means of a quadrant lever 59 as illustrated in Figure 6.

In the construction shown in Figure 6 the clutch 48 is operated by a link 60 connected to an arm 61 pivotally mounted within the casing and engaged by a roller pin 62 mounted on the spur gear 8. The pin being mounted on the spur gear will operate with a smoother action than will the mechanism operated by the pin on the swinging arm, which may be more desirable, and will not convey the shock incident to the other transmission.

In the operation of this machine the meat to be sliced is placed upon the tray 34 and the gripping levers are thrown down, the springs holding the gripper members in flexible contact therewith. The meat projects beyond the grippers and beyond the tray and slides on the longitudinally corrugated plate 32 and is fed up to the knife.

The rotation of the hand wheel then revolves the knife through the train of gears described and as the spur gear 8 revolves the roller pin carried thereby operates the knife carrying arm to swing forwardly and as the carriage is arranged considerably below the axis of the knife, the cutting will be effected mostly, if not entirely, below the centre and as the knife swings forwardly it also swings downwardly, thus making a downward cut which is most desirable as it cuts toward the solid support of the carriage and thus avoids cutting slices thick on one side.

The knife feeds forwardly at a moderate rate of speed as the operating pin travels around the outer portion of the orbit of the spur gear and following the completion of the forward movement, the pin moves inwardly toward the pivot and thus swings the knife back with an accelerated movement.

This peculiarity in the operation of the machine renders it very desirable as it effects a great saving of time.

What I claim as my invention is:—

1. In a slicing machine, the combination with a base, a swinging knife arm supported

from said base, a rotatable knife and means for rotating the knife, of an arm rigidly connected with said pivotal knife arm, a wheel operatively connected with the knife driving mechanism having a pin slidably engaging the latter arm and operating same with an accelerating return movement, and a carriage supported from said base at the end thereof opposite the aforesaid mechanism 5 and operatively connected therewith.

2. In a slicing machine, the combination with a base, a swinging knife arm supported from said base, a rotatable knife and means for rotating the knife, of an arm rigidly connected with the knife arm having a longitudinal slot therein, a gear wheel operating the knife rotating means and arranged in eccentric relation to the pivot of the knife arm, a pin arranged upon said 15 gear engaging the longitudinal slot in said slotted arm, a casing enclosing said gear and slotted arm arranged at one end of said base, and a carriage movable toward and from said casing, said knife arm operating between said casing and carriage. 20

3. In a slicing machine, the combination with a base, a knife arm pivotally mounted above the base and extending upwardly therefrom, a slotted arm secured to said 30 knife arm, a rotating knife, a train of gears arranged on said knife arm adapted to rotate said knife, a shaft extending through the pivot of the knife arm, a spur pinion mounted on said shaft adjacent to the slotted 35 arm, a spur gear meshing with said pinion, a pin carried by said spur gear and engaging the slot in said arm to swing said arm forwardly and to return the arm with an accelerated movement, a casing enclosing the 40 spur gear and slotted arm and supporting said spur gear, a fly wheel directly connected with said spur gear, and a carriage supported from the base at the opposite end to said casing. 45

4. In a slicing machine, the combination with a base, a swinging knife arm and rotatable means for rotating the knife and swinging the arm, of a slidable table, a worm shaft operatively connected to move 50 said slidable table, a ratchet clutch mounted on the worm shaft to rotate same in one direction, a link connected with said clutch, an arm pivotally connected at one end to said link and at the other end to a fixed 55 pivot, and a pin carried by the knife operat-

ing mechanism adapted to engage the latter arm to swing it on its pivot and operate the clutch.

5. In a slicing machine, the combination with a base, a swinging knife arm and rotatable means for rotating the knife and swinging the arm, of a slidable table, a worm shaft operatively connected to move said slidable table, a ratchet clutch mounted on said worm shaft adapted to rotate the same 60 to advance the table, means connected with the knife operating means for operating said clutch, a ratchet clutch mounted on said worm shaft adapted to prevent backward movement of the shaft, a pin extending laterally from the latter clutch, a pin extending laterally from the former clutch adapted to engage the former pin, and means for adjustably holding the latter clutch in a 65 fixed position. 70

6. In a slicing machine, the combination with a base, a swinging knife arm and rotatable means for rotating the knife and swinging the arm, of a slidable table, a worm shaft operatively connected to move 80 said slidable table, a ratchet clutch mounted on said worm shaft adapted to rotate the same to advance the table, means connected with the knife operating means for operating said clutch, a ratchet clutch mounted 85 on said worm shaft adapted to prevent backward movement of the shaft, a pin extending laterally from the latter clutch, a pin extending laterally from the former clutch adapted to engage the former pin, a 90 rod connected with the latter clutch extending through the base, and means for adjusting the position of said rod to effect an adjustment of the pin on the secondary clutch in relation to the pin on the shaft 95 operating clutch. 100

7. In a slicing machine, the combination with the base, an oscillating knife arm, a rotatable knife, and means for operating said knife, of a longitudinal movable table having a pair of upwardly extending arms, a bell crank arm mounted in each of the aforesaid arms, gripper members pivotally mounted on said bell crank arms, spring means for holding said gripper members in 105 contact with the goods to be cut, and a lever and a link pivotally connected together and to said bell crank arms.

CHARLES N. SOWDEN.
